FRANK BILLINGTON, OF PORTLAND, OREGON.

WATER-RESERVOIR FOR AUTOMOBILE-RADIATORS.

1,401,513.

Specification of Letters Patent. Patented Dec. 27, 1921.

Application filed January 5, 1920. Serial No. 349,663.

To all whom it may concern:

Be it known that I, FRANK BILLINGTON, a citizen of the United States, residing at Portland, in the county of Multnomah and State of Oregon, have invented a new and useful Water-Reservoir for Automobile Radiators, of which the following is a specification.

My invention relates to improvements in water reservoirs for automobile radiators in which separate containers are affixed to the top of the radiator.

The objects of my invention are:

First, to furnish an emergency supply of water for the radiator.

Second, to furnish a container which is applicable to any car.

Third, to furnish a container which does not interfere with the operation of the car.

Fourth, to place the container where the water can be preheated so that cracking of the cylinders from cold water is avoided.

I attain these objects with the mechanism illustrated in the accompanying drawing, in which—

Figure I is a front elevation of a radiator with my reservoir attached.

Fig. II is a plan view of Fig. I.

Similar numerals refer to similar parts throughout the several views.

The reservoirs 1 are complete metallic receptacles in themselves and are soldered to the top of the radiator 2 on both sides of the fill opening 3. An aperture 4 in the bottom of the receptacle discharges the contents when required into the interior of the radiator. This aperture is ordinarily closed by a valve 5, whose threaded stem 6 reaches through the top of the receptacle and can be turned by the T handle 7. The cylinder 8 which carries the female thread for the stem 6 is provided with a flange 9 and held to the top of the receptacle by the screws 10. The opening in the top through which the cylinder 8 passes should be large enough so

that the valve 5 can be withdrawn for repairs after screws 10 are removed, and the cylinder 8 should be long enough to provide a straight guide for the valve stem 6. The fill opening 11 for the reservoir 1 may be closed by a cover plate 12 or in any other suitable manner.

Having thus described my invention, it will be seen that my objects have been accomplished and, though I have shown the preferred form of construction, I reserve to myself the right to make any changes which do not contravene the principle of my invention.

I claim:

1. In a water reservoir for automobile radiators, the combination of a receptacle attached to the top of a radiator and having an opening leading from the receptacle to the radiator with a valve for closing said opening, said valve being accessible from the outside of the receptacle, substantially as described.

2. In a water reservoir for automobile radiators, the combination of a closed receptacle soldered to the top of a radiator, said receptacle having an inlet on top and an outlet at the lowest point of the bottom, said outlet communicating with the interior of the radiator, with a valve screwably mounted in the top of said receptacle and capable of opening or closing the outlet at the bottom, substantially as described.

3. In a water reservoir for automobile radiators, the combination of a receptacle soldered to the top of a radiator, having an inlet and an outlet, with a valve screwably mounted in a flange on top of the receptacle and capable of being withdrawn by unscrewing the flange from the top of the receptacle, substantially as set forth.

Signed by me at Portland, Oregon, this 13th day of December, 1919.

FRANK BILLINGTON.
